UNITED STATES PATENT OFFICE.

JOHN E. OSMER, OF CHICAGO, ILLINOIS, ASSIGNOR TO HUMPHREY COMPANY, OF KALAMAZOO, MICHIGAN.

AUTOMATIC WATER-HEATER.

1,134,406.

Specification of Letters Patent.

Patented Apr. 6, 1915.

Application filed August 15, 1910. Serial No. 577,268.

To all whom it may concern:

Be it known that I, JOHN E. OSMER, a citizen of the United States, residing at Chicago, in the county of Cook and State of Illinois, have invented certain new and useful Improvements in Automatic Water-Heaters, of which the following is a specification.

This invention relates to automatic water heaters in which the supply of fuel to the heater is varied in accordance with the temperature of the water therein.

The object of the invention, generally speaking, is to improve the valve mechanism with a view to greater simplicity and durability.

A specific object is to produce a water valve of novel construction.

Another object is to provide an improved connection between the water valve and the fuel valve.

Other objects and advantages will become apparent as the invention is better understood from the following detailed description.

In the accompanying drawings, Figure 1 is a diagrammatic view, partly in section, of an automatic water heating system embodying the features of my invention. Figure 2 is a sectional detail view of a thermostat comprised in the apparatus.

The heater proper may be of any desired construction and comprises, in the present instance, a casing 1 having a series of water pipe coils 2 therein arranged to be heated by means of a plurality of gas burners 3 in the lower portion of the casing 1. 4 indicates openings in the lower portion of the casing 1 to admit air to the burners 3. The water pipe coils 2 are connected with the water supply pipe 5 through the medium of a pipe 6 and a water valve casing 7 comprising the upper cylindrical section 7^a and the lower section 7^b, said casing having a piston 8 slidable therein. The piston 8 fits snugly in its casing 7, but a slight amount of leakage occurs around the piston from the space below said piston to the space above it. The amount of clearance indicated in Fig. 1 is much exaggerated for the sake of clearness. The water supply pipe 5 connected with the city main, or any other suitable source of supply of water under pressure, communicates with the casing 7, in this instance, below the piston 8. A valve

9 controls communication between the lower portion of the casing 7 and a chamber 10 at the under side of said casing, from which chamber the pipe 6 conducts the cold water to one of the water coils 2, preferably the upper one of the series. The valve 9 is connected to the piston 8 by lugs 11 on the valve and piston, said lugs being secured together. A port 9^a formed through the valve 9 connects the chamber 10 with the lower portion of the casing 7 for a purpose to appear hereinafter. Through said port the water in the heater 1 and in the chamber 25, even in case of leakage, is always under city water pressure. The outlet end of the water coils 2 in the present embodiment is connected through the medium of a pipe 12 with the lower end of a thermostat 13, the upper end of the thermostat communicating through means to be presently described with the upper end of the valve casing 7. The thermostat 13 may, if desired, be supported upon a bracket 14 fixed to or integral with the casing 7. Said thermostat in this instance comprises an outer tube 15 an inner tube 15' and an expansion rod 16 movably mounted within said inner tube. The lower ends of the tubes 15' and 15 are supported and the outer tube 15 is closed by means of a hollow head 17 having a nipple 18 thereon with which the pipe 12 is connected. Said head is connected with the interior of the outer tube 15 by a suitable number of ports 19. The upper ends of the tubes 14 and 15' are closed by means of a head 20 having a cavity 21 therein, said cavity being connected with the interior of the outer tube 15 through a plurality of ports 22. The expansion rod 16 extends freely through an opening 23 formed in the lower head 17, and is supported upon a lever to be later described. The upper and lower heads 20 and 17 may be secured together by means of bolts 24.

Upon the upper end of the water valve casing 7 is a chamber 25, the upper end of which is closed, in this instance, by the head 20, a passage 26 in said head connecting the cavity 21 with the interior of said chamber 25. A valve 27 arranged to seat in port 27' controls communication between the chamber 25 and the portion of the casing 7 above the piston 8. Said valve has a guide stem 28 arranged to be engaged and moved by the piston 8 to open the valve 27.

A spring 29 tends to hold the valve 27 seated. The piston 8 is normally pressed downwardly by means of a coiled spring 30. An exit pipe 31 for the hot water leads from the upper portion of the casing 7 to any suitable place, such as a storage tank 32 in the house-piping system. 33 is a faucet communicating with the pipe 31.

In order to regulate the distance to which the valve 27 may be opened, I may provide means such as a screw 34 threaded in the head 20 and adapted to be engaged by the valve 27 in its upward movement. The outer end of the screw 34 may be covered by means such as a cap 35 threaded upon a boss 36 on the upper side of the head 20. It will be seen that by regulating the distance which the valve 27 may open, the rate of flow of water through the heater, and therefore the temperature of the water, may be controlled, because the more slowly the water flows through the heater, the more heat it will absorb in its passage. By turning the screw 34 upward sufficiently the valve 27 is permitted to rise far enough to bring the lower end of its stem 28 flush with the downwardly extending flange of the port 27'. Then the elevation of piston 8 is limited by engagement with port 27', this engagement being practically water tight.

Gas or other fuel is supplied to the burners 3 by means of a pipe 37 which communicates with a valve casing 38 having a valve member 39 therein, adapted to control the passage of gas through the valve. The opposite side of said valve casing communicates with the burners 3 through a pipe 40. 41 is a coiled spring tending to hold the valve 39 closed. The valve 39 is arranged to be controlled by the thermostat 13 through the medium of suitable devices such as a number of levers 42, one of which levers supports and is adapted to be swung downward by the expansion rod 16 of the thermostat, and another of which levers is arranged to engage the valve stem 39^a of the valve member 39. An adjusting screw 43 mounted in one of the levers 42 provides means for regulating the movement of the valve member 39. As shown, the valve stem 39^a preferably extends entirely through the casing 38.

When the hot water passing through the thermostat 13 reaches a predetermined temperature, the expansion rod 16 will be lengthened sufficiently to seat the valve member 39 through the medium of the levers 42 so as to cut off the supply of gas to burners 3. A branch pipe 44 communicating with the gas supply pipe 37 is adapted to conduct gas at all times to a pilot burner 45.

A supporting member, in this instance in the form of a bar 46, is attached at its upper

end to the water valve casing 7 and has a slot 47 in its lower end, in which slot is mounted a pin 48 carried by a lever 49. A link 50 slidably mounted in the lower wall of the chamber 10 is connected at one end to the lever 49 between its ends and at its other end to the valve member 9. One end of the lever 49 is arranged to engage the lower end of the fuel valve stem 39^a for opening the valve 39. The other end of said lever is arranged to be yieldingly held down by any suitable means such as a weight 50' or a coiled spring 51 surrounding the bar 46 and bearing at its ends against the lever 49 and a pin 52 fixed in the bar 46. A screw 53 adjustably carried by the lever 49 is arranged to strike against the fuel valve casing 38 for the purpose of limiting the extent to which the fuel valve 39 may be opened. As will be seen, the lever 49, bar 46 and link 50 constitute a lost motion connection between the water inlet valve 9 and the gas valve 39.

Assuming the entire apparatus to be filled with water, the operation is as follows: 90 When water is drawn off from the house piping system, as for instance, through the faucet 33, the pressure in the upper portion of the casing 7 is lowered and the piston 8 is therefore forced upwardly against the action of the coiled spring 30 by the city water pressure in the lower half of the casing. In its upward movement the piston 8 opens the valve 27 to admit hot water from the heating coils 2 to the valve casing 7. 100 The piston 8 also raises the valve member 9 to permit the flow of water from the lower portion of the casing 7 to the heating coils. In its upward movement the valve member 9, through the medium of the link 50 and 105 lever 49, raises the valve member 39 to allow the passage of gas through the pipes 37 and 40 to the burners 3 so that the cold water flowing into the coils 2 will be heated.

In case the water in the thermostat is at 110 a temperature such that the expansion rod 16 is holding the gas valve 39 closed, if a small amount of water be drawn off from the faucet 33, the upward movement of the piston 8 and valve member 9 will not be 115 effective in opening the gas valve 39, but will raise the lever 49 with the valve casing 38 as a fulcrum, said lever moving against the action of the weight 50' and spring 51. When the faucet 33 is again closed the pressures in opposite sides of the casing 7 become equal and the spring 30 forces the piston 8 downwardly far enough to permit the valve 27 to seat. In the further downward movement of the piston to close the cold 125 water inlet valve 9, water gradually leaks around the periphery of the piston 8 into the upper portion of the casing 7 so as to permit the piston 8 to descend. The closing of the valve 9 carries the lever 49 into posi- 130

tion to permit the gas valve 39 to be closed by its spring 41 so that the supply of gas to the burners 3 will be shut off.

If for any reason the gas valve 39 should not be closed either by its spring 41 or the thermostat 13, the pressure of the hot water or steam within the heater, if it becomes greater than the city water pressure, will force water back through the port 9^a in the cold water valve 9 into the casing 7 to relieve the pressure in the heater.

I would have it understood that I do not limit myself to the details of construction herein shown and described, as various modifications within the scope of my invention will occur to those skilled in the art.

I claim as my invention:

1. The combination, with a water heater, of a valve casing communicating therewith; a piston slidably mounted in said casing; said casing having an inlet and an outlet for cold water at one side of said piston; said casing having an inlet and an outlet for hot water at the opposite side of said piston; valves controlling certain of said inlets and outlets, said valves being operable by said piston; a fuel valve; and a connection between one of the first mentioned valves and said fuel valve.

2. The combination with a water heater, of valve mechanism comprising a casing; a piston slidably mounted in said casing, said casing having an entrance for cold water at one side of said piston, the casing at said side of the piston communicating with said heater, said casing having a hot water outlet at the opposite side of said piston; and a conductor between the heater and the hot water side of said casing including a valve, said valve being adapted to be opened by said piston.

3. The combination, with a water heater, of a fuel valve having an oppositely extending valve stem; a spring tending to close said valve; a thermostat; means positioned between said thermostat and one end of said valve stem arranged to communicate motion of said thermostat to said stem for closing the fuel valve; a water-inlet valve; a lever; a link connecting said lever between its ends to said water inlet valve, one end of said lever being arranged to engage the opposite end of said fuel valve stem for opening the fuel valve; and means tending to move the opposite end of said lever in the direction away from said water-inlet valve.

4. The combination, with a water heater, of valve mechanism communicating therewith, said mechanism comprising a casing; a piston slidably mounted in said casing, said casing having an inlet and an outlet for cold water at one side of said piston, and having an inlet and an outlet for hot water at the opposite side of said piston; a valve arranged to control communication between

said cold water inlet and outlet; and a valve controlling communication between said hot water inlet and outlet, said valves being operable by said piston.

5. The combination with a water heater, of valve mechanism comprising a casing; a piston slidably mounted in said casing; said casing having an entrance for cold water at one side of said piston; a chamber adjacent the casing at said side of the piston; said chamber communicating with said heater; a valve connected with said piston and controlling communication between said chamber and the casing; said casing having a hot water outlet at the opposite side of said piston; a chamber on said casing adjacent said hot water outlet, the last mentioned chamber communicating with said heater; and a valve controlling communication between the last mentioned chamber and the hot water side of said casing, the last mentioned valve being operable by said piston.

6. The combination, with a water heater, of a valve casing communicating therewith; a piston slidably mounted in said casing; said casing having an inlet and an outlet for cold water at one side of said piston; said casing having an inlet and an outlet for hot water at the opposite side of said piston; a valve operable by said piston and controlling communication between said hot water inlet and outlet; a valve operable by said piston and controlling communication between said cold water inlet and outlet; a valve controlling the supply of fuel to said heater; and a connection between said fuel valve and cold water valve.

7. The combination, with a water heater, of a valve casing communicating therewith; a piston slidably mounted in said casing; said casing having an inlet and an outlet for hot water at one side of said piston; said casing having an inlet and an outlet for cold water at the opposite side of said piston; a valve operable by said piston and controlling communication between the last mentioned inlet and outlet; a valve controlling the supply of fuel to said heater; a lever; a link connecting the middle portion of said lever with said cold water valve, one end of said lever being arranged to bear against said fuel valve for opening it; means for supporting the opposite end of said lever and permitting said opposite end to rise; and means tending to hold said opposite end down.

8. The combination, with a water heater, of a valve casing; a piston slidably mounted in said casing; a chamber at one side of said casing arranged to receive hot water from said heater; said casing having an opening from said chamber into said casing at one side of said piston; said casing having an outlet for hot water; a valve controlling the flow of hot water through said opening;

means tending to hold said valve closed, said valve being arranged to be opened by said piston; a chamber on said valve casing at the opposite side of said piston; said casing having an inlet for cold water at the last mentioned side of said piston, the last mentioned chamber communicating with said heater; said casing having an opening from the last mentioned side of said casing to said 10 chamber; a valve operable by said piston and controlling the flow of the cold water through said opening; a valve controlling the supply of fuel to said heater; and a connection between the two last mentioned 15 valves.

9. The combination, with a water heater, of a valve casing; a piston slidably mounted in said casing; a chamber on said casing at one side of said piston; a thermostat adjacent said chamber; a head closing said chamber and one end of said thermostat; said head having a passage communicating with said chamber and said thermostat; a pipe connecting the opposite end of said thermostat with said water heater and adapted to conduct hot water from said heater to said thermostat; a valve controlling communication between said chamber and said casing at one side of said piston; means tending 20 to hold said valve closed, said valve being operable by said piston, said casing having a hot water outlet and a cold water inlet leading from opposite sides of said piston, the last mentioned side of said casing 25 communicating with said heater; a valve controlling the flow of cold water from said casing to said heater; a valve arranged to control the supply of fuel to said heater; and a lost motion connection between the two 30 last mentioned valves adapted to open said fuel valve, said fuel valve being adapted to be closed by said thermostat.

10. The combination with a water heater, of a water inlet valve; a fuel valve; a connection 45 between said valves; a thermostat communicating with the outlet from said heater, said thermostat comprising an outer tube, an inner tube, a pair of heads closing the ends of said tubes, said heads having passages therein communicating with the interior of the outer tube only; an expansion rod movably mounted within said inner tube, and extending through an opening in one of said heads; and means upon which the lower end 50 of said expansion rod rests, said means being arranged to be operated by the expansion of said rod to close said fuel valve.

11. The combination with a water heater, of a valve casing; a piston slidably mounted 60 in said valve casing; a chamber on said casing at one side of said piston; a pipe connecting said chamber with the inlet to said heater; said casing having an inlet for cold water at said side of said casing; a valve operable by said piston and controlling com-

munication between said casing and said chamber; a valve arranged to control the supply of fuel to said heater; a lost motion connection between said valves; a chamber on said casing at the opposite side of said 70 piston; a pipe connecting the last mentioned chamber with the outlet from said heater; said casing having a hot water outlet at the last mentioned side of said piston; a valve controlling communication between the last 75 mentioned chamber and the casing, said valve being adapted to be opened by said piston; a coiled spring resisting movement of said piston in the direction to open said valve; a coiled spring tending to hold said 80 valve closed; a thermostat communicating at one end with said heater, a head closing the opposite end of said thermostat and the end of the last mentioned chamber, said casing having a passage connecting the interior 85 of said chamber with said thermostat, and means operable by the expansion of said thermostat adapted to close said fuel valve.

12. The combination with a water heater, of a valve casing communicating therewith; 90 a piston slidably mounted in said casing; a valve connected with said piston and controlling communication between said heater and said casing at one side of said piston, said valve having a port therethrough; said 95 casing having an inlet for cold water at said side of the piston; a valve arranged to control the supply of fuel to said heater; a lost motion connection between said valves adapted to open said fuel valve; said casing 100 having an outlet for hot water at the opposite side of said casing; a chamber on said casing adjacent said outlet; a valve controlling communication between said chamber and said casing and adapted to be opened by 105 said piston; means tending to hold said valve closed; adjustable means for limiting the opening movement of said valve; a thermostat communicating at one end with said heater; a head closing the opposite end of 110 said thermostat and the upper end of said chamber, said head having a passage therein connecting said chamber with said thermostat; and means positioned between said thermostat and said fuel valve, said means 115 being arranged to magnify the expansion of said thermostat and transmit the motion thereof to said fuel valve for closing the valve.

13. The combination with a water heater, 120 of a water inlet valve; a fuel valve; a rigid frame for said fuel valve; a connection between said valves adapted to open said fuel valve; and a thermostat communicating with the outlet from said heater and having 125 one end rigidly mounted on said frame, said thermostat comprising an outer tube and an inner tube, said tubes being connected by perforated head members arranged for the transmission of fluid therethrough and 130

- through the outer tube, and an expansion rod lying loosely within said inner tube, and rod-supporting means arranged to communicate motion therefrom to said fuel valve 5 for closing the latter.
14. The combination with a water heater, of a fuel valve; a water inlet valve; a connection between said valves for operating said fuel valve when said water valve is 10 opened; a hot water outlet check valve automatically opened by said water inlet valve, said water valves opening against the normal water pressure; an outlet faucet; and means operable by said water pressure for 15 opening said valves when said faucet is open.
15. The combination with a water heater, of a fuel valve; a water inlet valve; a connection between said valves for operating 20 said fuel valve; a hot water outlet valve; and means to automatically open said inlet valve upon the withdrawal of water from said heater, and means for opening said outlet valve, said means for opening said outlet 25 valve being dependent upon the operation of said means for opening said inlet valve.
16. The combination with a water heater, of a valve casing; a piston slidably mounted in said casing, said casing having an entrance and an exit for cold water at one side 30 of said piston, said casing having an entrance and exit for hot water at the other side of said piston; said cold water exit and said hot water entrance connected with said 35 water heater; a valve in each of said connections; said cold water valve having a relatively small vent therethrough; means for automatically opening said valves upon withdrawal of water through said hot water 40 exit; a fuel valve; and operative connection between said fuel valve and said cold water valve.
17. The combination with a water heater, of a valve casing; a piston slidably mounted 45 in said casing, said casing having an entrance and an exit for cold water at one side of said piston, said casing having an entrance and exit for hot water at the other side of said casing, said cold water exit and 50 said hot water entrance being connected with said water heater; a valve in each of said connections; means for automatically opening said valves upon withdrawal of water through said hot water exit; a fuel valve; 55 and operative connection between said fuel valve and said cold water valve.
18. The combination with a water heater,
- of a valve casing; a piston in said casing; a thermostat; a head for said valve casing and one end of said thermostat provided 60 with a communicating passage, the opposite end of said thermostat being connected with the heater; an inlet valve controlled by said piston; a valve arranged to control the supply of fuel to said heater; and connections between said inlet valve and said fuel valve adapted to open said fuel valve, said fuel valve being adapted to be closed by said thermostat.
19. The combination with a water heater, 70 of a fuel valve; a water inlet valve; operating connections for said water inlet valve to said fuel valve comprising a lever, a support with which said lever has a pin and slot connection; a spring acting on said connection to hold the lever at one end of the slot; a link connecting said lever to said inlet valve; and a thermostat mechanism arranged to act on said valve to close the same independently of said water valve connections thereto.
20. The combination with a water heater, 75 of a valve casing; a piston slidably mounted in said casing; said casing having an entrance and an exit for cold water at one side of said piston, said casing having an entrance and exit for hot water at the other side of said piston; said cold water exit and said hot water entrance connected with said water heater; a valve in each of said connections; means for automatically opening 80 said valves upon withdrawal of water through said hot water exit; a fuel valve; and operative connection between said fuel valve and said cold water valve.
21. The combination with a water heater, 95 of a valve casing; a piston in said casing; said casing having an entrance and an exit for cold water at one side of said piston and an entrance and exit for hot water on the other side of said piston; said cold water exit and said hot water entrance being connected with said water heater; a cold water valve having a relatively small vent therefrom; said piston being automatically moved 100 to open the water inlet valve on the withdrawal of water from the hot water exit; a fuel valve; and operative connections with said fuel valve and piston.
